UNITED STATES PATENT OFFICE.

ALBERT SONDHEIMER, OF CLEVELAND, OHIO.

BOWLING-BALL.

1,080,307.

Specification of Letters Patent.

Patented Dec. 2, 1913.

Application filed August 2, 1911. Serial No. 641,883.

To all whom it may concern:

Be it known that I, ALBERT SONDHEIMER, a citizen of the United States, and a resident of Cleveland, county of Cuyahoga, and State 5 of Ohio, have invented a new and useful Improvement in Bowling-Balls, of which the following is a specification, the principle of the invention being herein explained and the best mode in which I have contemplated 10 applying that principle, so as to distinguish it from other inventions.

My invention relates to a removable bushing for bowling balls adapted to contain the recesses commonly known as the hand-holes by which the ball is gripped by the bowler. Not only are my improved bushings removable, but by offsetting the holes at different distances from the center of the bushing, I am able to adjust the hand grip 20 to different bowlers by merely changing the bushings.

The hand-holes have heretofore been a constant source of trouble and expense in the maintenance of bowling balls in first 25 class conditions. With the lignum-vitæ ball, the hand-holes were sometimes bored in the balls, or a permanent hard rubber bushing was put in. Neither method was satisfactory. The plain holes chipped away very 30 rapidly at the top, leaving the edge ragged and uncomfortable to the hand. If a rubber bushing was used to prevent chipping, the moisture of the hand combined with the constant friction would so smooth the 35 bushing that it gave a very poor grip and the ball would tend to slip when the bowler was about to release it. Of course, new bushings could be inserted, but this was impossible without tools and the balls had to 40 be sent to the factory, necessitating considerable expense and loss of time. The present bushing obviates both these difficulties, giving an easily removable bushing which does not chip nor become smooth. 45 To the accomplishment of the aforesaid and related objects, said invention, then, consists of the means hereinafter fully described and particularly pointed out in the claims.

The annexed drawings and the following 50 description set forth in detail certain mechanism embodying the invention, such disclosed means constituting, however, but one of the various mechanical forms in which the principle of the invention may be used. 55 In said annexed drawings:—Figure 1 is a central sectional view of a bowling ball

having my improved bushings; Fig. 2 is a side elevation of my bushing; Fig. 3 is a side elevation of a quick-locking bushing; and Fig. 4 is a central section of a recess in 60 a bowling ball adapted to receive the bushing in Fig. 3; Fig. 5 is a cross sectional view of the bushing shown in Fig. 3 in engagement with the recess of Fig. 4; Fig. 6 is a similar view showing the bushing 65 when rotated into engagement with the threaded recess.

In Fig. 1, the bowling ball 1 is shown having the two removable bushings 2 one of which may be threaded into the recesses 3. 70 The bushings have cylindrical recesses 4 which may be disposed either concentrically, or more or less eccentrically, thus permitting different spacing between the recesses by the insertion of variously recessed bushings. The bushings are held in secure engagement with the ball as shown. When not threaded the bushings are securely held by screws 5. These screws may readily be removed and the bushing taken out and a 75 new one inserted should one become chipped or too smooth. Neither is liable to happen, as I preferably use some tough material such as fiber which does not chip and becomes smooth only after long use. Even better 80 than a fiber bushing is one made of such material as rubber ducking, or some similar composition, which is tough, preferably 85 homogeneous and very enduring.

In Fig. 2 I illustrate a bushing comprising 90 an upper surface layer of fiber and a lower layer of wood. This latter bushing combines the good qualities of the rubber bushing, for the upper portion does not chip, and also the superiority of the wood, for 95 the grip is chiefly on the lower portion and the wood receives the same and does not become slippery.

It will be noticed that in Fig. 2 the disposition of the recesses in the bushing is at an 100 angle to a central line through the bushing, as shown by the dotted lines in this figure. By means of this construction, the bowler is enabled to get a more secure grip on the bushings, since the two recesses may be so 105 disposed that they are inclined to each other at a greater angle than if they were merely radially inset in the bushings.

It will be obvious that the recesses in the bushings may be eccentrically disposed with 110 respect to the central line of the bushing, and also at an angle to such central line,

as illustrated in Figs. 1 and 2. When the recess in the bushing is both eccentric and at an angle to the central line of the bushing there can be but little adjustment of the bushing by rotation since the advantage of the inclination of the recesses to the central lines is thereby lost, and the grip secured is not as good, or at the best no better than if the recesses were eccentric but parallel with the central lines of the bushings.

All of the bushings embody the principle of my invention by being removable and adjustable and are of materials superior in every way to that which was suitable for the bushings heretofore used.

In Figs. 3 and 4 I illustrate a ball and a bushing therefor which may be instantly adjusted and yet is in secure engagement. On the opposite quadrants of the threaded recess I cut out the threads and do the same to the threads on the bushings. Thus in one relative position (see Fig. 6) the bushing will easily slip into the recess, when a quarter turn will cause engagement of the threading, (see Fig. 5) and the screws may or may not be used to lock the bushing in engagement.

The adjustment feature of my bushings I regard as little less important than the removable feature. Bowling balls are at present made with the spacing between the holes of certain standard dimensions. This makes it necessary for manufacturers and dealers to carry in stock an excessive number of balls of each weight and diameter because of the different distances between the holes. By using my bushings the holes can all be set at a given distance and the variously apertured bushings can be used to adjust the spacing of the holes to the individual requirement. It will be seen therefore, that the use of my new and improved bushing cheapens the cost of manufacture by cutting down the amount of stock which must be kept on hand, and greatly lessens the cost of keeping the balls in good repair with regard to the hand-holes. Finally, it provides a rapid and simple means for perfectly fitting the grip in a bowling ball to any individual.

Other modes of applying the principle of my invention may be employed instead of the one explained change being made as regards the mechanism herein disclosed, provided the means stated by any of the following claims or the equivalent of such stated means be employed.

I therefore particularly point out and distinctly claim as my invention:—

1. The combination with a bowling ball having a recess therein; of a bushing adapted to removably engage such recess, said bushing having an eccentrically disposed aperture therein.

2. The combination with a bowling ball having a recess therein; of a bushing adapted to removably engage such recess, said bushing having an aperture disposed therein, the axial lines of such recess and such aperture being mutually inclined with relation to each other.

3. The combination with a bowling ball having a recess therein; of a bushing adapted to removably engage such recess, said bushing having a substantially smooth-walled cylindrical aperture disposed therein, the axial lines of such recess and such aperture being mutually inclined with relation to each other.

4. The combination with a bowling ball having a recess therein; of a bushing adapted to removably engage such recess, said bushing having an eccentrically disposed aperture therein, and means adapted to prevent said bushing from turning during use.

5. The combination with a bowling ball having a plurality of recesses therein; of a plurality of bushings adapted to snugly engage said recesses; each of said bushings having an eccentrically disposed aperture therein; and means connecting said ball and said bushings, whereby the latter cannot rotate during use.

6. The combination with a bowling ball having two radially disposed cylindrical threaded recesses spaced from each other; of two bushings adapted to enter such recesses until flush with the surface of said ball, said bushings having cylindrical recesses eccentrically disposed therein and oblique with the central axis of said bushings, whereby the spacing between such recesses may be varied by substituting bushings having the recesses therein of greater or less eccentricity, thus permitting the fitting of the recesses to the grip of different bowlers as desired; and screws adapted to securely retain said bushings in said ball.

Signed by me this 31st day of July, 1911.

ALBERT SONDHEIMER.
